DESIGN FOR A RIDGE PLATE OR SIMILAR ARTICLE

Roy E. Lushbaugh, New Albany, Ind.

Application June 13, 1946, Serial No. 130,662

Term of patent 3½ years

(Cl. D54—2)

To all whom it may concern:

Be it known that I, Roy E. Lushbaugh, a citizen of the United States and resident of the city of New Albany, in the county of Floyd and the State of Indiana, have invented a new, original, and ornamental Design for a Ridge Plate or Similar Article, of which the following is a specification, reference being had to the accompanying drawings, forming a part thereof:

Fig. 1 is a perspective view of a ridge plate showing my new design.

Fig. 2 is a side view of the same.

Fig. 3 is an end view of the same.

The essential features of my design are shown in full lines.

I claim:

The ornamental design for a ridge plate or similar article, as shown and described.

ROY E. LUSHBAUGH.
